NECKTIE

Filed May 24, 1928

Inventor
N. B. Nelson

By Watson E. Coleman.

Attorney

UNITED STATES PATENT OFFICE.

NELS B. NELSON, OF ELGIN, ILLINOIS.

NECKTIE.

Application filed May 24, 1928. Serial No. 280,356.

This invention relates to neckties and it is an object of the invention to provide a tie which can be readily and conveniently applied and removed without the necessity of 5 tying or untying and which can be worn with equal facility in connection with a soft or stiff collar.

It is also an object of the invention to provide a device of this kind wherein the connecting member between the tie sections is of a pliable or flexible character assuring effective fitting or setting of the tie at the front of the collar.

The invention consists in the details of 15 construction and in the combination and arrangement of the several parts of my improved necktie whereby certain important advantages are attained and the device rendered simpler, less expensive and otherwise 20 more convenient and advantageous for use, as will be hereinafter more fully set forth.

The novel features of my invention will hereinafter be definitely claimed.

In order that my invention may be the better understood, I will now proceed to describe 25 the same with reference to the accompanying drawings, wherein:

Figure 1 is a fragmentary view in elevation illustrating a necktie constructed in accordance with an embodiment of my invention partly assembled;

Figure 2 is a view similar to Figure 1 showing a further assembly of the necktie;

Figure 3 is a view in plan of the connecting member as herein embodied unapplied:

Figure 4 is a view in perspective with portions broken away of a necktie constructed in accordance with the present embodiment of my invention and with the sections of the tie unknotted.

As disclosed in the accompanying drawing, my improved necktie comprises the tie sections 1 of desired lengths and of a character to permit the same to be tied or connected in the well known fashion of a four-in-hand. An end portion of each of the sections 1 is formed to provide a sheath 2 to receive an end portion of a connecting member 3 highly pliable in character and which may be produced from leather or other kindred material. A wall of each of the tie sections 1 at the inner end of the sheath 2 is provided transversely thereof with a slot 4 to permit the desired insertion 55 of an end portion of the member 3 therein,

said slot 4 in one of the sections being in the rear wall and in the second section in the front wall.

The central portion of the member 3 is provided with a pair of longitudinally spaced 60 and relatively large openings 5 herein disclosed as substantially rectangular in form and in close proximity one to the other.

The end portions of the sections 1 provided with the sheaths 2 are disposed through 65 said openings 5 before the end portions of the member 3 are inserted within the sheaths 2.

The end portions of the member 3 extend within the sheaths 2 and terminate adjacent 70 the outer ends of said sheaths. By this arrangement the stitching 7 for holding the eye member 6 to one of the sections 1 will be disposed through an end portion of the member 3 while the stitching 7' for connecting the 75 elastic band 8 to the second section 1 will be directed through the opposite end portion of the member 3. By this means the stitchings 7 and 7' provide effective means for maintaining the member 3 in desired assembled 80 relation with respect to the sections 1. This band 8 is provided at its outer portion with an adjustable loop 9 with which is operatively engaged a hook member 10 for conventional coaction with the eye member 6. The tie sections 1 are then connected in a well known 85 manner to produce a finished tie of a four-in-hand type, or of such other style as may be preferred in accordance with the exact character of the tie sections 1.

It is also to be noted that in assembling the tie sections 1 and the member 3, said tie sections immediately to the rear of the member 3 are in crossed relation and that initially, or before tying the sections 1, said sections 90 are in reverse relation so that the desired knot will be properly formed with the dressed surfaces of both of the sections 1 properly exposed.

From the foregoing description it is 100 thought to be obvious that a necktie constructed in accordance with my invention is particularly well adapted for use by reason of the convenience and facility with which it may be assembled and operated, and it will 105 also be obvious that my invention is susceptible of some change and modification without departing from the principles and spirit thereof and for this reason I do not wish to be understood as limiting myself to the pre- 110

cise arrangement and formation of the several parts herein shown in carrying out my invention in practice except as hereinafter claimed.

5 I claim:—

A necktie comprising two tie sections, an end portion of each of said sections being provided with a sheath, a wall of which having an entrance opening at the inner end of 10 the sheath, a pliable connecting member hav-

ing an end portion insertible within the sheath of each tie section, the central portion of said member having spaced openings through which end portions of the tie sections are inserted, a collar encircling means for 15 connecting the end portions of the tie sections provided with the sheaths.

In testimony whereof I hereunto affix my signature.

NELS B. NELSON
